UNITED STATES PATENT OFFICE.

FRANK A. WILLIAMS, OF HOLLEY, ASSIGNOR OF ONE-HALF TO EDWARD T. LAMB, OF BATAVIA, NEW YORK.

WIRE-FABRIC MACHINE.

SPECIFICATION forming part of Letters Patent No. 517,508, dated April 3, 1894.

Application filed November 17, 1892. Serial No. 452,244. (No model.)

To all whom it may concern:

Be it known that I, FRANK A. WILLIAMS, of Holley, in the county of Orleans and State of New York, have invented a certain new and useful Improvement in Wire-Fabric Machines; and I do hereby declare that the following is a full, clear, and exact description of the same, reference being had to the drawings accompanying this application.

10 My improvement relates to machines for weaving wire fabric. It is applicable, more particularly, to weaving wire fences of that class where the longitudinal wires are first attached to the posts and the filling is then 15 woven in.

The invention consists in the construction hereinafter described and definitely claimed.

In the drawings—Figure 1 is a side elevation of the machine and a portion of fence 20 which it is in the act of weaving. Fig. 2 is a front elevation looking in the direction of the arrow at the right in Fig. 1. Fig. 3 is a rear elevation looking in the direction of the arrow at the left in Fig. 1. Fig. 4 is an enlarged horizontal cross section in line $x-x$ of Figs. 2 and 3. Fig. 5 is a diagram showing in elevation the manner of shifting the gears.

25 This invention relates to that class in which segment twisters are used carrying the filling wires; which segmental twisters are alternately moved up and down for the purpose of crossing the filling wires from one to another of the longitudinal strands.

30 A indicates the main frame, which is provided with wheels $a a$ that roll forward on a platform B as the work progresses, being kept in place by guides $b b$.

35 C C are two slides on two opposite sides, which move up and down in the main frame, 40 being connected at their top by a pivoted rock lever c and two connecting rods $d d$. By this means when one slide is thrown up the other is thrown down and vice versa. The throw of the slides is equal to the distance 45 apart of the longitudinal strands of the fence.

40 D D and D' D' are two series of twisters, attached respectively to the two slides and moving with them in reverse directions. Each twister consists of a segment composed 50 of two half-heads $f g$, with a circular groove h between them, in which groove fits the con-

cave edge i of the slide, by which means the segment turns freely but is held to the slide as the latter moves up and down. The head f is formed with a set of gear teeth $k k$; and 55 with the teeth of one of the twisters engages a pinion l , attached to a shaft m , having its bearings in one of the slides, and provided with a crank n . The pinion being carried up and down by the slide remains in permanent engagement with this particular twister.

E E are a set of tubular spindles attached fast to the main frame. The longitudinal wires $j j$ of the fence pass freely through these spindles.

60 $o o$ are a series of center blocks mounted on the spindles so as to turn freely, but having no longitudinal or vertical movement. They, in fact, form sections which fit between the twisters when brought to position, and 65 are provided with gear teeth $k' k'$ and grooves $h' h'$ corresponding with those of the twisters. By this means when the segmental twisters are brought in alignment with the center blocks complete circular heads are formed 70 which turn freely between the opposing edges of the slides, and each head forms a gear wheel driven by the pinion on the outer side. As the ends of the center blocks all gear together the rotary motion imparted to one of 75 the heads by the pinion is transmitted to all of them.

Each alternate pair of the twisting heads is provided with brackets $p p$ on the heads $g g$, which brackets support the bobbins $r r$ that 80 hold the filling wires. These filling wires pass out through holes $s s$ in the brackets and connect with the main wires. The upper and lower twisters of the set, however, have each but a single bracket p which is attached to 85 one segment. In this construction it is necessary to use half twisters D² one above and the other below the main twisters, and arranged on opposite sides as shown. They perform no twisting action, but are necessary 90 to complete the gears of the upper and lower twisters as the slides are moved up and down. Otherwise no rotation would be given to the upper and lower twisters. In order to preserve the proper position of these half heads 95 so that they can be moved in connection with the other twisters, they run in contact with

guides t which hold them in place. The guides correspond in shape and position with the center blocks o between the gears.

In practice only a single filling wire is wound around each of the extreme longitudinal wires of the fence, hence but a single bracket and bobbin is necessary at each of those points. But double filling wires are wound on all of the intermediate longitudinal wires at intervals of every other wire. At these points double brackets and bobbins are required.

The method of changing the twisters from one wire to another is illustrated in the diagram Fig. 5, which shows the upper twister at the left moving down and the lower one at the right moving up. When they align with the lower center block they complete the gear, which can then be revolved by the pinion any desired number of times.

By the construction above described the machine is in simpler and more compact form and is much lighter to operate than ordinary machines, since the gears and the twisters are combined together forming a single set of revolving heads; whereas, in ordinary machines the gears and heads are widely separated and are connected by bars. This machine also differs from others in being driven by a pinion on the outside attached to one of the slides and engaging with the external gear teeth, while in other machines motion is imparted to the twisters by an inner section.

The machine is propelled forward by means of the ordinary rack and gear u operated by hand lever v , and the slides are reciprocated up and down by a hand lever w , or any other suitable means.

Having described my invention, I do not

claim broadly reversible twister heads and 40 slides; but

What I claim as new, and desire to secure by Letters Patent, is—

1. In a wire fence machine, the combination of the reversible slides, the series of twisters 45 attached thereto and movable with the slides, and center blocks with which the twisters align when in position, said twisters and center blocks being provided on their outer edges with gear teeth with which engages an external gear for giving rotary motion to the twisters, as herein shown and described.

2. The combination, with the segmental twisters attached to suitable supports and movable in reverse directions, of the stationary center blocks capable of rotary motion, the twisters and blocks provided with gear teeth, and so arranged that when the twisters are brought in alignment with the blocks complete circular toothed heads are formed, 60 as herein shown and described.

3. The combination, with the main frame, of the reversible slides, the toothed center blocks attached to suitable supports, the toothed twister heads connected with the 65 slides so as to be carried up and down with them, and the pinion l and its shaft m attached to one of the slides, said pinion engaging with the gear of one of the twister heads, in the manner and for the purpose 70 specified.

In witness whereof I have hereunto signed my name in the presence of two subscribing witnesses.

FRANK A. WILLIAMS.
